[57] CLAIM

The ornamental design for a saw guide, as shown and described.

DESCRIPTION

FIG. 1 is a top and right front isometric view of a saw guide showing my new design, with the movable tongue set in a central position;

FIG. 2 is a front elevational view thereof;

FIG. 3 is a front elevational view thereof, with the tongue set in a horizontal position;

FIG. 4 is a right side elevational view of FIG. 3.
